SANITARY GARBAGE CONTAINER

William H. Willey, Kansas City, Mo.

Application February 15, 1932, Serial No. 592,922

4 Claims. (Cl. 193—34)

This invention relates to a sanitary garbage container, and more particularly to a garbage container so arranged that garbage can be delivered thereto from a kitchen without the necessity of leaving the kitchen.

The present manner of disposing of kitchen garbage is to place it in a receptacle in the kitchen and let it stand until a convenient time arrives to carry it out to the garbage receptacle proper.

10 The handling of garbage in this manner is objectionable in that it is unsightly and quickly acquires a bad odor, also drawing vermin. This is especially true when the garbage remains in a warm kitchen for some time.

15 By the use of my device, however, the garbage from each meal can be readily disposed of, that is, it can be delivered to the main garbage receptacle without leaving the kitchen. Consequently, there will be no garbage standing about the 20 kitchen.

Another important feature is that the main garbage receptacle is so located that while it can readily be reached by the garbage collector it will be protected from animals such as dogs, cats 25 etc., and consequently there will be no upset garbage receptacles or garbage scattered about to create a nuisance.

Another important feature is that the device is so arranged and vented that no odor from 30 the garbage will enter the kitchen.

The auxiliary garbage receptacle is so arranged and located that garbage will drain therefrom and pass into the waste pipe of a sink in which the receptacle is designed to be located.

35 Another feature is that the door to the chute used in connection with my device is a part of the back of the sink and opens and closes automatically. Therefore, no unsightly openings are present, and the sink is provided with a sliding 40 top so that the auxiliary container can be concealed.

In accomplishing these and other objects of my invention, I have provided improved details of structure, the preferred forms of which are 45 shown in the accompanying drawings, wherein:

Fig. 1 is a vertical section of my device with part broken away showing the same installed in a house.

50 Fig. 2 is a fragmental vertical section of my device showing the chute closure in opened position.

Fig. 3 is a horizontal section taken on the line 3—3, Fig. 1.

55 Fig. 4 is a fragmental perspective view of the auxiliary container and closure opening levers.

Fig. 5 is a horizontal section taken on the line 5—5, Fig. 1.

Fig. 6 is a view of the lower portion of my device with part in section, showing the manner of releasing the primary garbage receptacle from 60 the chute.

Referring to the drawings in detail:

1 represents the outer wall of a house, 2 an inner wall, and 3 the floor.

Secured to the wall 2 is the back 4 of a sink 5 having the usual waste or drain pipe 6 and a strainer 7. A plate 8 is slidably mounted adjacent the upper edge of the sink so that the sink can be closed and used as a temporary table or shelf.

70 Formed through the back 4 of the sink is an opening 9 which is provided with a closure 10 having a rod 11 secured to its upper edge. The rod projects beyond both side edges of the closure and these projecting ends are pivotally mounted 75 in ears 12 projecting from the back 4. A weight 13 is secured to the rear face of the closure 10 which aids in moving the closure into closed position. The lower portion of the closure is bent rearwardly as at 14, the purpose of which will 80 be explained later. Cam bars 15 are secured to the rear face of the closure parallel to and adjacent the side edges of said closure.

85 Projecting rearwardly from the back 4 and adjacent the lower edge of the opening 9 are ears 16 in which a rod or shaft 17 is rotatably mounted. Rigidly secured to the shaft 17 is the upper edge of the rear wall 19 of the auxiliary garbage container 20, which has its bottom, side and rear walls perforated or reticulated so that 90 it will not retain moisture. The back wall is inclined upwardly and rearwardly so that when the container 20 is raised into the position shown, garbage will slide readily thereover. The container normally rests in the sink as shown, and 95 is provided on its front wall with a knob or handhold 21 so that it can be easily raised. The container is of a width slightly less than that of the opening 9 in the back 4, thus permitting it to swing partly into the opening when raised.

100 Rigidly secured to the shaft 17 are arms or levers 22 having their free ends inturned as at 23. Loosely mounted on the shaft are the short arms 24 of an L-shaped lever, the long arms 25 of which have their ends inturned as at 26, which inturned ends are designed to contact the cam bars 15 for the purpose of opening the closure 10.

105 Extending upwardly between the walls 1 and 2 is a casing or chute 27, its upper end being provided with a cowl 28 which extends through the 110

wall 2. The cowl surrounds the opening 9 in the sink back 4 and is provided with an outwardly extending flange 29 which is designed to be attached to the back 4.

5 The cowl 28 is also provided with an opening 30 which is surrounded by a pipe flange 31 in which a pipe 32 is secured. The pipe 32 communicates with the atmosphere outside the building and serves as a vent for the chute 27, carrying off odors and gases rising from the garbage and preventing them from entering the room.

10 The lower end of the chute 27 extends into a casing 33 and is provided with a hood 34 designed to surround the upper end of a main 15 garbage receptacle 35. The hood is held in position by means of straps 36 which are attached to it and to certain walls of the casing.

15 The casing 33 is provided in one of its side walls with a closure or door 37 hinged at its lower edge, the closure being so arranged as to be operable from without the building, and is held in closed position by means of a suitable latch 38.

20 The closure is provided with arms 39 secured to its inner face which are designed to contact levers 40 pivoted intermediate their ends in

25 brackets 41 secured to the bottom of the casing 33. It will be observed from Fig. 5 that the levers parallel the side walls 42 of the casing adjacent the closure. Pivoted secured to the inner ends of the levers 40 are links 43 which are also pivotally secured to a false bottom or platform 44. The pivots 45 which secure the links 43 to the false bottom 44 extend beyond the links 35 and operate in slides or guides 46 carried by the side walls 42, and thus restrain the bottom 44 against any horizontal movement.

30 The casing 33 is preferably of the insulated type so that garbage in the receptacle will not freeze, and while I have shown the casing as

35 being located inside the building, I do not desire to be limited to this particular location, as in certain instances it may be desirable or necessary to locate it on the outside of the building.

40 It will also be noted that the closure 10 can be opened by merely pushing against it and independently of any movement of the auxiliary garbage receptacle, permitting liquid garbage to be thrown into the chute.

45 The operation of my device is as follows:

50 After the installation has been completed, the door 37 is opened and the garbage receptacle 35 is placed on the false bottom 44. The door 37 is then closed and during the closing the arms 39 contact the levers 40, causing them to move on their pivots, and through the links 43 raise the bottom 44, thereby raising the receptacle 35 so that its upper end will enter the hood 34.

55 When it is desired to empty garbage from the auxiliary receptacle 20, the handhold or knob 21 is grasped and the front end of the receptacle is raised, causing rotation of the shaft 17 which, as before-stated, is firmly attached to the upper edge of the rear wall 19 of the receptacle.

60 The rotation of the shaft 17 also causes the arms 22 to swing backwardly and downwardly, and brings their inturned ends 23 into contact with the arms 24 of the L-shaped levers. Continued movement of the receptacle 20 and, consequently, of the arms 22, causes these levers, which are loosely mounted on the shaft 17, to swing, moving the long arms 25 thereof backwardly, bringing the inturned ends 26 of these arms into contact with the cam bars 15 carried by the closure

sure 10, and, in moving along these bars, open the closure.

When the closure is fully opened, as shown in Fig. 2, the auxiliary receptacle is in substantially a vertical position and its contents discharge into the chute automatically. When it is desired to empty garbage which will not be retained in the receptacle 20, the closure 10 may be opened by pushing against the same. This opening is permitted by reason of the L-shaped levers being loosely mounted on the shaft 17 and, consequently, the closure 10 can be opened without disturbing the container 20.

It will be noted from the foregoing that the container 20 becomes interlocked with the closure opening mechanism only after it has been moved some distance.

When it is desired to remove the receptacle 35, the closure 37 is opened. This moves the arms 39 away from the levers 40, permitting the bottom 44 to move downwardly and free the top end of the receptacle 35 from the hood 34.

The counterweight 13 is made sufficiently heavy so that the closure 10 will not be swung to and fro by draft which would cause a disagreeable noise.

While I have shown only one auxiliary receptacle pivotally mounted in an opening in the chute, it is to be understood that the chute may be extended upwardly any number of floors and have an opening in its side wall at every floor, with a pivotally mounted auxiliary receptacle for each opening. Of course, in such construction, the cowl 28, with its vent, would only be placed at the uppermost opening. This construction is adaptable for apartment buildings, as it eliminates the carrying of garbage through the halls and provides a single main garbage container for a number of apartments.

What I claim and desire to secure by Letters Patent is:

1. In apparatus of the character described, a chute including a side wall having an opening, a hinged closure for said opening, a shaft rotatably supported parallel to and adjacent the opening by said side wall, an auxiliary container fixed to the shaft, cam bars on the closure, levers rotatably mounted on the shaft and operably engaged with the cam bars, and arms fixed on the shaft and operably connected with

12 said levers to effect opening of the closure in response to rotation of the shaft by said container. 2. In apparatus of the character described including a chute having a side wall provided with an opening, a closure member, means for hingeing the closure member in the opening, a container, means for pivotally mounting the container to swing toward said opening, a lever arm movable with the container, a second lever arm pivotally associated with the container, and 18 adapted to be engaged by the first named lever arm upon swinging movement of the container to actuate the last named arm, and means on the closure member engaging said last named arm to effect opening of the closure member upon swinging movement of the container.

3. In apparatus of the character described including a chute having a side wall provided with an opening, a closure member, means for hingeing the closure member in the opening, a container, means for pivotally mounting the container to swing toward said opening, a lever arm movable with the container, a second lever arm pivotally associated with the container and adapted to be engaged by the first named lever

arm upon swinging movement of the container to actuate the last named arm, and a cam bar on the closure member engaged by the last named arm to effect opening of the closure member upon 5 swinging movement of the container.

4. In an apparatus of the character described including a chute having a wall provided with an opening, a container, means pivotally mounting the container in said opening, a closure member, means pivotally supporting the closure member in the opening and having a lower portion co-

operating with the container to close said opening, an arm member movable with the container, a second arm member engageable with the first arm member and lost motion means connecting said second named arm with the closure member to effect opening of the closure member upon swinging movement of the container and to allow independent opening of the closure member independently of movement of the container. 80
